(57) **CLAIM**

The ornamental design for a rocking foot rest, as shown and described.

DESCRIPTION

FIG. 1 is a bottom, front and left side perspective view of a rocking foot rest showing my new design;
FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an exploded perspective view thereof; and,

FIG. 9 is an enlarged view of the portion labeled "9" framed in FIG. 1.

In FIG. 1 and FIG. 9, a dot-dash broken line rectangular frame defines the boundary of an enlarged view and form no part of the claimed design.
